SELF-PROPELLED MECHANICAL SHOVEL

Charles J. Davis, 22 Colonial, Wichita, Kans.

Filed Dec. 31, 1964, Ser. No. 83,245

Term of patent 14 years

(Cl. D40—1)

FIG. 1

FIG. 2

FIG. 3

FIG. 4

FIG. 5

FIG. 6

FIG. 1 is a left side view of a vehicle embodying my new design, the wheels being shown in the respective positions they occupy during operation of the shovel;

FIG. 2 is a rear end view of the same;

FIG. 3 is a front end view of the same;

FIG. 4 is a right side view of the same;

FIG. 5 is a top plan view of the same;

FIG. 6 is a three-quarter rear perspective view of the same; and

FIG. 7 is a side elevation similar to FIG. 1 with towing hitch member in an alternate position.

I claim:

The ornamental design for a self-propelled mechanical shovel, as shown.
